UNITED STATES PATENT OFFICE.

HARRY F. HANSEN, OF WASHINGTON, DISTRICT OF COLUMBIA.

NONGLARE HEADLIGHT.

Application filed October 17, 1923. Serial No. 669,096.

To all whom it may concern:

Be it known that I, HARRY F. HANSEN, a citizen of the United States, residing at Washington, in the District of Columbia, 5 have invented new and useful Improvements in Nonglare Headlights, of which the following is a specification.

This invention relates to non-glare headlights for use on motor cars; its object, 10 briefly stated, being the provision of an improved article of the character indicated which is so constructed that the light rays emitted by the lamp or other source of light are directed forwardly and laterally only, 15 all upward reflection being blocked, whereby the blinding effect of the lights on drivers of other vehicles approaching from the opposite direction is completely avoided.

According to the invention, the improved 20 headlight embodies primarily a specially constructed reflector unit which, in horizontal section, has the form of a semi-ellipse but which, in transverse vertical section, is shaped somewhat like an elongated, horizontally-disposed rectangle, the lower side of which is open and the corners of which are more or less bowed or rounded depending upon the distance of the section from the front. This element is closed at its bottom by a flat, semi-elliptic plate which, in 25 a sense, may be regarded as forming the bottom wall or base thereof; and the said plate, which is removably related to the reflector proper and constitutes the true bottom of the headlight casing, is suitably treated to 30 provide a dead-black surface, instead of being polished or silvered, in order to prevent any reflecting action.

Due to this peculiar construction, it will 35 be understood that the light rays will be reflected horizontally, both directly forward as well as laterally, by the vertical side wall of the reflector, and downwardly upon the blackened surface of the plate 40 by the flat top wall and by the rounded edge portions of the first-named wall; but, on the other hand, no upward reflection whatever will take place because of the aforesaid blackened surface, which will also 45 absorb all rays reflected downward upon it. Hence the light beam projected by the headlight will travel straight ahead at a distance from the ground too short to dazzle the eyes of drivers of approaching vehicles, so that one great cause of collisions 50 and other road accidents is thereby removed.

An embodiment of the invention is illustrated in the accompanying drawing, in which:

Figure 1 is a perspective view of the reflector body. 60

Fig. 2 is a horizontal sectional view showing the same in place in the headlight casing.

Figs. 3, 4 and 5 are diagrammatic transverse sections taken one back of another on lines 3—3, 4—4 and 5—5 of Fig. 1. 65

Fig. 6 is a plan view of the bottom member of the reflector and casing.

Fig. 7 is a front view of the headlight. 70

Referring more particularly to the drawing, the reflector unit comprises a body or reflector proper 9 and a base 10, the two being separate parts detachably related to each other, and the base also forming the bottom member of the subsequently-described casing, as hereinafter explained. The reflector body has the general shape of a semi-ellipse in horizontal, longitudinal section and consists of a flat horizontal top wall 9' and a curved vertical side wall 9²; said body being constructed of metal and having the inner surfaces of its walls polished, silvered or otherwise treated to obtain a reflection action. At the front of the reflector body, the meeting edges of the walls 9' and 9² form a right angle, as shown in Fig. 1; but at a point about one inch from the front they are slightly rounded, as indicated in Fig. 3; and from that point on, the rounding grows more pronounced as will be understood from Fig. 4, which is a section taken about two inches to the rear of section 3—3 until a point is reached about an inch in the rear of section 4—4 80

where the lower edge of wall 9² also becomes curved or rounded, as shown in Fig. 5, so that said wall is there of concavo-convex section. The curvature from the last-named point continues around the back of the reflector; this special formation holding true, of course, for both sides of the reflector; that is to say, the reflector body is of symmetrical construction, its curvature and the rounding of its edges being the same at 85 both sides of its vertical median line. The electric lamp bulb 11, or other source of light, is attached to the rear portion of the wall 9² at the center thereof, by means of the usual fitting 11', or in some other suitable way. 90

The base member 10 of the reflector unit

has the form of a flat plate, of substantially the same shape as, but slightly larger than, the top wall 9' of the reflector body. This plate has a blackened or otherwise treated 5 upper surface to absorb all light rays falling thereon, and on it directly rests the lower edge of the reflector wall 9², the two plates or walls 9' and 10 thus being disposed in spaced, parallel relation. The reflector 10 body and the base plate 10 are removably related, as has already been mentioned, the object being to facilitate access to the lamp 11 and to enable the base plate to be detached, when desired, for cleaning or other 15 purposes. To that end, the reflector body is secured in some suitable manner within the casing 12 of the headlight: for instance, by providing the front edges of its component walls 9' and 9² with projecting 20 flanges 9³ and 9⁴ which are fastened to the corresponding edges of the top and side walls 12' and 12² of said casing.

The aforesaid casing has the same shape and substantially the same height and width 25 as the reflector body, but is of somewhat greater depth; and it includes, in addition to the walls 12' and 12², a swinging front wall or door 12³ which is provided with a suitable lens 12⁴ and has a hinge connection 30 12⁵ at one end with one end of wall 12² of the casing, its other end being detachably clamped to the opposite end of said wall as indicated at 12⁶. The bottom plate or member 10 which, as previously stated, 35 is common to the casing as well as to the reflector body 9, has approximately the same shape and size as the top wall 12' of the casing and is connected at its rear end to the lower edge of the vertical side wall 12² 40 of the casing at the center thereof by means of a hinge joint 10', the pintle of which is preferably removable so that, if desired, the said plate may be completely detached from the casing. At its front end, the plate is 45 removably supported by the front wall or door 12³ which is provided upon its inner face with a rib or shoulder 12⁷ to take under the plate when the door is closed; the arrangement being such that when the door 50 is opened, the plate would tend to swing downward, unless restrained in some manner. An upstanding, semi-elliptic flange 10² is finally provided on the plate, adjacent to and parallel with its marginal edge, which 55 is designed to fit tightly against the inner face of the vertical casing wall 12² and, by reason of such engagement, serves to hold said plate in place.

As will be apparent from the foregoing, 60 the most important feature of the invention is the obliteration of all upwardly-reflected light rays, leaving only those projected horizontally, so as to avoid blinding. This is accomplished by the conjoint action of 65 the reflector body and the non-reflecting

plate 10 constructed as above described. The lamp 11, being supported midway between the top and bottom walls of the reflector unit, will, of course, cast its rays in all directions, those striking against the 70 vertical side wall 9² of the reflector being reflected horizontally both forward and laterally, while those which strike against the top wall 9' will be reflected downward against the bottom wall or plate 10, as will 75 be understood. The curved upper edges of the side wall 9² will also exert a downward reflecting action on the rays striking thereagainst, and these reflected rays will likewise fall upon the plate 10; but by reason 80 of the vertical disposition of the said wall wall 9², none of the rays which strike against it will be reflected upward, in contradistinction to the action, so to speak, which takes 85 place in an ordinary conical or semi-ellipsoidal reflector. On the other hand, all of the rays which fall upon the bottom plate 10, whether projected directly thereagainst by the source of light or reflected 90 by the top wall or the bowed or rounded portions of the side wall of the reflector body, and which would ordinarily be reflected upward by the said plate, are completely absorbed by the blackened surface 95 thereof and, hence, will not emerge from the headlight. Consequently, the effect of the improved construction is to insure the projection from the headlight of a light beam which travels horizontally forward at a height which is equal to the distance of 100 the light source from the road, and which maintains such height virtually constant throughout its travel. And since the horizontal plane of the light source in the headlights of an ordinary car is disposed a distance of several feet below the plane of 105 the eyes of the driver, it will be obvious that the light beam will strike a car approaching from the opposite direction at a 110 corresponding distance below the eyes of the driver of the latter car, with a complete avoidance of dazzling or blinding.

In all other respects, the invention is believed to be apparent from the foregoing, and to require no further explanation.

I claim as my invention:

1. A non-glare headlight, comprising a casing which is semi-elliptic in horizontal section and substantially rectangular in transverse, vertical section; a reflector unit of approximately the same shape as said casing disposed within the same; a source of light projecting into the interior of the reflector from the central rear portion thereof; and a base plate constituting a common bottom for the casing and the reflector and connected to the former, said plate having a non-reflecting upper surface; substantially as described.

2. A non-glare headlight, comprising a

casing which is semi-elliptical in horizontal section and substantially rectangular in transverse, vertical section; a reflector unit of approximately the same shape as said 5 casing disposed within the same; a source of light projecting into the interior of the reflector from the central rear portion thereof; and a base plate constituting a common bottom for the casing and the reflector 10 and detachably connected to the vertical side of the former, said plate having its upper surface blackened; substantially as described.

3. A non-glare headlight, comprising a 15 casing; a reflector disposed therewithin and embodying side and top walls; a source of light in said casing; a base plate substantially parallel with the top wall of the reflector, and constituting a common bottom for the casing and the reflector whereon 20 the lower edges of the side walls of the reflector normally directly rest, said base

plate having a non-reflecting upper surface and being removably connected to said casing, but devoid of connection with said reflector to permit the latter to be withdrawn 25 bodily from the casing.

4. A non-glare headlight, comprising a casing embodying a side wall and a top wall; a reflector unit disposed therewithin; 30 a source of light in said casing; a base plate constituting a common bottom for the casing and the reflector unit but structurally separate from both said parts, and having a non-reflecting upper surface, said plate being hinged to the lower edge of the side wall of the casing so as to swing downward 35 into open position and thereby permit the reflector unit to be withdrawn bodily from the casing; and means for detachably connecting said base plate in horizontal, closed position.

In testimony whereof I affix my signature.

HARRY F. HANSEN.
